Primary Examiner — Kevin K Rudzinski*Assistant Examiner* — Woosuk K Shin(74) *Attorney, Agent, or Firm* — Kirk A. Buhler; Buhler & Associates Patenting(57) **CLAIM**

The ornamental design for a skin-to-skin nursing cover as shown and described.

DESCRIPTION

FIG. 1 is a front perspective view for a skin-to-skin nursing cover showing my new design;

FIG. 2 is a front side view shown in a flat position;

FIG. 3 is a right side view thereof;

FIG. 4 is a top side view thereof;

FIG. 5 is a back side view thereof;

FIG. 6 is a left side view thereof;

FIG. 7 is a bottom side view thereof;

FIG. 8 is a top side view folded through the neck opening thereof;

FIG. 9 is a back side view folded through the neck opening thereof;

FIG. 10 is a right-side view folded through the neck opening the left side view being a mirror image thereof;

FIG. 11 is a bottom side view folded through the neck opening thereof; and,

FIG. 12 is a front perspective view shown in an environment of use thereof.

The broken line showing of a person and text is for the purpose of illustrating environmental structure that form no part of the claimed design.
